UNITED STATES PATENT OFFICE.

FRED B. ROBINSON, OF FORT WINFIELD SCOTT, CALIFORNIA.

STREET AND STATION INDICATOR.

1,260,712.

Specification of Letters Patent. Patented Mar. 26, 1918.

Application filed February 6, 1917. Serial No. 146,880.

To all whom it may concern:

Be it known that I, FRED B. ROBINSON, a citizen of the United States, and a resident of Fort Winfield Scott, in the county of San Francisco and State of California, have invented a certain new and useful Improvement in Street and Station Indicators, of which the following is a specification.

My invention relates to improvements in street and station indicators, and it consists in the combinations, constructions, and arrangements herein described and claimed.

An object of my invention is to provide a device by means of which the name of streets may be indicated to the passengers in a street car, railway train, or the like before such street is reached.

A further object of my invention is to provide an electrically controlled indicating mechanism of a novel type.

A further object of my invention is to provide an indicating mechanism in which the movements of the display device is controlled by means of a pneumatically operated mechanism, the latter being in turn controlled by electrical switches in the manner hereinafter described.

Other objects and advantages will appear in the following specification, and the novel features of the invention will be particularly pointed out in the appended claims.

My invention is illustrated in the accompanying drawings forming part of this application, in which:

Fig. 1 is a diagrammatic view of the electrical circuits and the mechanism connected therewith.

Fig. 2 is a detailed view of a contact closing device.

Fig. 3 is a sectional view through a portion of the device.

Fig. 4 is a perspective view showing the means for connecting the spindle rollers.

Fig. 5 is a face view of the transmission mechanism.

Fig. 6 is a face view of the casing of the indicator and the display window.

Fig. 7 is a section on the line 7-7 of Fig. 6, and

Fig. 8 is a view of one of the rollers, a portion of the roller being shown in section.

The invention described herein may be used in connection with street railways, railroad systems, etc. That form illustrated in the drawings is applied to a street rail-

way. It will be seen that the device may be applied to railroad systems without departing from the spirit of the invention in general.

Considering now Fig. 1, it will be seen that the car 1 is provided with a conducting shoe 2, which is curved at its ends, as shown at 3. The shoe is suspended from an insulating bar 4 secured to the car by means of brackets 5. Bolts 6 are arranged to slide through the insulating support 4, these bolts being attached to the shoe 2, while springs 8 are provided for cushioning movement of the shoe.

Arranged to coöperate with shoe 2 is a contact 9 of the form shown in Fig. 2. This consists of a conducting head carried upon a bracket 10, which is secured to the rail 11 in the manner shown, being provided with an attaching arm 10^a and a brass member 10^b arranged to engage the rail base, thus forming an exceedingly strong and rigid construction.

In certain instances these contacts may be located on both sides of the track, as for instance, with steam and conduit electric lines. In the present instance, however, the contacts are placed on one rail only. There are two of these contacts for each block. They are both located at equal distances from the respective streets at the ends of the block, say approximately at 50 feet from the end.

A shoe such as that shown at 2 may be provided on the opposite side of the car if desired.

Referring again to Fig. 1, M' is a magnet which controls switch arm S, the latter being pivotally connected at s to a slidable switch member K. A solenoid M² has its core m pivotally connected at d to switch arm D which is pivotally mounted at dx. A solenoid or magnet M³ has a double winding and its core is also connected with the arm D at d. In the circuit controlled by the arm D is a solenoid M⁴, whose core m⁴ is connected with the stem 12 of a valve 13 carried by the cylinder 14.

Referring now to Fig. 3, it will be seen that the valve 13 controls an intake pipe 15 and an exhaust pipe 16. The exhaust pipe is shown in Fig. 3 as being in communication with the interior of the cylinder 14 through an exhaust passage 14^b, while the intake pipe is adapted to communicate with the

interior of the cylinder 14 through a port 14^a when the valve is shifted.

The cylinder is provided with a piston P whose stem *p* is surrounded by a spiral 5 spring 17. The stem passes out through the end of the cylinder, and is provided at its end with a rack 18. A contact closing arm 19 having an insulating head 20 is carried by the stem *p*.

10 Referring now particularly to Fig. 5 I have shown therein a transmission mechanism which converts reciprocatory movement of the rack 18 into intermittent rotary movement, which is always in the same 15 direction. To this end I provide a stationary shaft 21 upon which is rotatably mounted a sleeve 22, bearing a gear 23 in engagement with the rack 18. At the end of the sleeve 22 are clutch members 22^a and 22^b, 20 arranged to engage companion clutch members 23^a and 23^b, respectively. The clutch member 23^a is at the end of a sleeve 24, which is integrally connected with a bevel gear 25. The latter is arranged to engage 25 a bevel gear 26 when the gear 23 is turning in one direction, and to be thrown out of mesh with the gear 26 when the gear 23 is turning in the opposite direction. The clutch member 23^b is on the sleeve 27 bearing 30 a bevel gear 28, which is arranged to engage the opposite side of the gear 26 at a time when the gear 25 is out of engagement. Both of the gears 25 and 28 have springs 29 which tend to force them into engagement with the gear 26.

It will be obvious that when the rack 18 is moving upwardly in Fig. 5, the gear 23 will rotate in the direction shown by the curved arrows. This will cause the clutch 40 member 22^b to engage the clutch member 23^b and rotate the gear 28, thus tending to rotate gear 26 in the direction shown by the curved arrow. At the same time the rotation of the clutch member 22^a will cause 45 an outward movement of the gear 25 through the cam action of the clutch members 22^a and 23^a as the teeth slide over on one another. The gear 25 being pushed outwardly against the tension of the spring 29 50 permits the gear 26 to rotate freely.

The means for displaying names of the streets is best shown in Figs. 3, 6 and 7. It consists of a casing 30 having windows 31 and 32 on opposite sides thereof. As will be 55 seen from Fig. 7, the window 31 is near one end of the casing, while the window 32 is near the other end. The casing 30 is mounted on pivots 33 at the center of the casing and may be revolved so as to bring the windows 31 or 32 in the position shown in Fig. 6.

Disposed within the casing are the rollers 34 and 35, respectively. These rollers are free to turn, each roller being provided with 60 an axle such as those shown at 34^x and 35^x.

These axles are prolonged at one end and are provided with a male clutch member 34^c which is arranged to engage the female clutch member 36^c on the shaft 36, which bears the gear 26. The axles 34^x and 35^x are 70 slidable longitudinally, but are prevented from rotating by means of the feather or key such as that shown at 34^k in Fig. 4. In Fig. 8 I have shown the axle 34^x as extended and as being provided with a knob 75 34ⁿ. A spring 34^a keeps the axle normally in a position in which the clutch member 34^c is extended, that is to say, is forced toward the female clutch member 36^c. In order to disengage these clutch members it is 80 only necessary to pull the knob 34^a outwardly when the casing may be reversed on its pivot so as to bring the axle of the other roller into position to engage the clutch member 36^c. Wound on the rollers 34 and 85 35 is a strip of flexible material 37, which bears the names of streets, the names of the streets on one side of the strip being in the reverse order from the names on the other side. 90

From the foregoing description of the various parts of the device the operation thereof may be readily understood.

Let us assume that a street car has passed a street and is approaching one of the contacts. The engagement of the shoe 2 with the contact 9 causes the energization of the magnet M^a, current flowing by the following path: from the positive wire through 40, switch H, switch arm S, 41, through 100 winding of magnet M^a, 42, slide switch K, 43, shoe 2, 9, and to ground or if a metallic return is used to the source of current by said metallic conductor. This will move the switch arm D over to the right in 105 Fig. 1, whereupon current will be caused to flow from the positive wire through 44, outer winding of the magnet M^a, contact 45, D 46, 47, magnet M^b, wire 48 to the opposite or negative conductor. It will be observed that the outer and inner coils of the magnet M^a are wound so as to augment and 110 not oppose each other. The outer coil of magnet M^a forms a locking circuit for holding the switch arm D in position after the 115 shoe 2 has left the contact 9.

The magnet or solenoid M^b on being energized draws in its core m⁴ and moves valve 13 into position shown in Fig. 1. The intake pipe 15 is connected with a suitable 120 source of compressed air, not shown, and the air is admitted through the port 14^a into the interior of the cylinder 14, driving the piston P before it and compressing the spring 17. The movement of the piston rod 125 p causes the movement of the rack 18, see Fig. 5, and the rotation of the gear 26 in the manner already described. This causes the turning of the roller 34 connected with the gear a definite distance so as to bring 130

the name of the next street into view before the window.

- When the head 20 on the arm 19 engages the contact 49 it will push the latter into engagement with the spring contact 50, see Fig. 1, whereupon current will flow from the positive wire through 52, 50, 49, 53, magnet M' and by wire 54 to the negative conductor. The head 20 is adjusted to engage the spring contact 49 when the piston P has reached the end of its stroke. The switch arm S is now moved to as to break contact with the wire 41 and make contact with the wire 55 and at the same time the 15 slideable member K is moved to break contact with the wire 42 and to make contact with the wire 56. This puts the magnet M² in condition to be energized when the shoe 2 again engages a contact 9. 20 The closing of the contacts at 49-50 switches on electric lights 60, which illuminate the name of the street, see Fig. 6.
- The car now continues on its way and eventually the shoe 2 will engage the contact 9, near the end of the block. When this occurs current will flow from the positive wire through 40, H, S, 55, M², 56, K, 25 43, 9, to the negative line. The action of the magnet M² pulls the switch arm D from the full line to the dotted line position shown in Fig. 1, thereby breaking the locking circuit of the solenoid or magnet M⁴. The spring 65 which controls the valve stem 12 now pushes the valve 13 from the position shown in Fig. 1 to that shown in Fig. 3, cutting off the air from the intake pipe 15, and opening the exhaust pipe 16 to the interior of the cylinder 14. The exhaust pipe 16 is larger than the intake pipe, so that 30 air may be exhausted rapidly. The spring 17 now forces the piston P to the opposite end of the cylinder, and this moves the valve stem P and the rack 18. The first movement of the stem P breaks the contacts at 45 49 and 50, and this deenergizes the solenoid M', allowing the spring A² to pull the arm S backwardly, into the position shown in Fig. 1, at the same time moving the slideable switch member K.
- In the meantime a further movement of the piston P will cause the rack 18 to turn the roller through the medium of the transmission mechanism shown in Fig. 5 so as, to bring a blank space before the window 31. 50 This completes the cycle. When the shoe strikes the next contact, the cycle is begun again.

When the end of the line is reached, and the return trip begins, the casing 30 is released by pulling outwardly on the handle 34^a so as to release the clutch members 34^c and 36^c. The opposite side of the flexible strip 37 is then brought into view. It is obvious that as the flexible strip is wound off from one roller on to the other, the dif-

ference in the thickness of the roller will cause a greater or less linear movement of the flexible strip past the window. In order to compensate for this I make the letters which form the names of the street and the 70 spaces between adjacent names wider or narrower as the case may be so that no matter how thick the roller is the apparatus will move the roller so as to bring the name to the proper position for the 75 window.

It may be necessary for a car to pass a contact such as that shown at 9, and then retrace its route, as for instance, when the car has to back up to permit a snow plow, 80 sand car or other emergency car to pass. This might tend to interfere with the proper working of the device and to prevent such a contingency I provide a switch H, which 85 controls the electric valve controlling mechanism. The conductor may open this switch and then run the car back and forth as much as he pleases, taking care, however, to close the switch in order to give the correct indication when the car has proceeded 90 on its run.

It is obvious that the lights 60 will remain on while the name of the street is being displayed, but will be extinguished as soon as the contacts 49, 50, are broken or in 95 other words, while the roller is shifting from a street name to a blank space. It will furthermore be obvious that when the piston stem p moves outwardly the name of a street will be brought into view; when 100 it moves inwardly, a blank space will be brought into registration with the window 31.

I am aware that other forms of the device might be made to accomplish the results 105 above, but I consider as my own all the modifications which fairly fall within the spirit and scope of the claims.

I claim:

1. In a street indicating system for vehicles, a casing, a roller rotatably disposed at each end of the casing, a flexible strip carried by one roller and having a portion wound on the other roller, a pair of windows in the casing, one of said windows being disposed in one side of the casing near one of said rollers and the other on the opposite side near the other roller, the said casing being mounted to rotate on an axis parallel with the axis of the rollers and disposed on a line midway between them. 110

2. In a street indicating system for vehicles, a casing, a roller rotatably disposed at each end of the casing, a flexible strip carried by one roller and having a portion 115 wound on the other roller, a pair of windows in the casing, one of said windows being disposed in one side of the casing near one of said rollers and the other on the opposite side near the other roller, the said casing be- 120

130

- ing mounted to rotate on an axis parallel with the axis of the rollers and disposed on a line midway between them a clutch member carried by the shaft of each of said 5 rollers, a driving mechanism and a clutch member carried by the driving mechanism and arranged to be engaged by the clutch member of either of said rollers.
3. In a street indicating system for vehicles, a cylinder, a piston therein, a piston rod or stem, a valve in said casing for admitting air, a spring for returning the piston to its normal position, means for converting the reciprocatory movement of the 10 piston stem to rotary movement in the same direction, said means comprising a rack carried by the piston stem, a pinion arranged to be engaged by the rack, a main bevel gear, a pair of auxiliary bevel gears adapted to 15 engage said main bevel gear, and clutch members between said pinion and each of said auxiliary bevel gears for connecting and disconnecting said pinion from said auxiliary gears.
4. In a street indicating system for vehicles, a cylinder, a piston therein, a piston rod or stem, a valve in said casing for admitting air, a spring for returning the piston to its normal position, means for converting the reciprocatory movement of the 20 piston stem to rotary movement in the same direction, said means comprising a rack carried by the piston stem, a pinion arranged to be engaged by the rack, a main bevel gear, a pair of auxiliary bevel gears adapted to 25 engage said main bevel gear, and means disposed between each of said auxiliary bevel gears, and said pinion for bringing said auxiliary gear out of mesh with the main bevel gear when the pinion is revolving in a 30 certain direction.
5. In a street indicating system for vehicles, a casing having windows, a movable flexible strip having names arranged to 35 move past the window, means for operating the flexible strip, said means including a pneumatic device, a valve for controlling the pneumatic device, an electro-magnetic piston for controlling said valve, said electro- 40 magnetic system comprising a solenoid connected with the valve, a switch for actuating the solenoid, a magnet for operating the 45 switch, a shoe carried by the vehicle, and contacts disposed along the track and arranged to be engaged by the shoe for completing a circuit through the switch operating magnet. 50
6. In a street indicating system for vehicles, a casing having a window, a movable flexible strip having names arranged to move past the window, means for operating the flexible strip, said means including a pneumatic device, a valve for controlling the pneumatic device, an electro-magnetic device for controlling said valve, said electro-magnetic device comprising a solenoid connected with the valve, a switch for actuating the solenoid, a magnet for operating the switch, a shoe carried by the vehicle, contacts disposed along the track and arranged to be engaged by the shoe for completing a circuit through the switch operating magnet, said switch operating magnet being provided with a locking circuit for holding said switch when the shoe has passed the contact. 55
7. In a street indicating system for vehicles, a casing having windows, a movable flexible strip having names arranged to move past the window, means for operating the flexible strip, said means including a pneumatic device, a valve for controlling the pneumatic device, an electro-magnetic device for controlling said valve, said electro-magnetic device comprising a solenoid connected with the valve, a switch for actuating the solenoid, a magnet for operating the switch, a shoe carried by the vehicle, contacts disposed along the track and arranged to be engaged by the shoe for completing a circuit through the switch operating magnet, said switch operating magnet being provided with a locking circuit for holding said switch when the shoe has passed the contact. 60
8. In a street indicating system for vehicles, a casing having windows, a movable flexible strip having names arranged to move past the window, means for operating the flexible strip, said means including a pneumatic device, a valve for controlling the pneumatic device, an electro-magnetic device for controlling said valve, said electro-magnetic device comprising a solenoid connected with the valve, a switch for actuating the solenoid, a magnet for operating the switch, a shoe carried by the vehicle, contacts disposed along the track and arranged to be engaged by the shoe for completing a circuit through the switch operating magnet, said switch operating magnet being provided with a locking circuit for holding said switch when the shoe has passed the contact. 65
9. In a street indicating system for vehicles, a casing having windows, a movable flexible strip having names arranged to move past the window, means for operating the flexible strip, said means including a pneumatic device, a valve for controlling the pneumatic device, an electro-magnetic device for controlling said valve, said electro-magnetic device comprising a solenoid connected with the valve, a switch for actuating the solenoid, a magnet for operating the switch, a shoe carried by the vehicle, contacts disposed along the track and arranged to be engaged by the shoe for completing a circuit through the switch operating magnet, said switch operating magnet being provided with a locking circuit for holding said switch when the shoe has passed the contact. 70
10. In a street indicating system for vehicles, a casing having windows, a movable flexible strip having names arranged to move past the window, means for operating the flexible strip, said means including a pneumatic device, a valve for controlling the pneumatic device, an electro-magnetic device for controlling said valve, said electro-magnetic device comprising a solenoid connected with the valve, a switch for actuating the solenoid, a magnet for operating the switch, a shoe carried by the vehicle, contacts disposed along the track and arranged to be engaged by the shoe for completing a circuit through the switch operating magnet, said switch operating magnet being provided with a locking circuit for holding said switch when the shoe has passed the contact. 75
11. In a street indicating system for vehicles, a casing having windows, a movable flexible strip having names arranged to move past the window, means for operating the flexible strip, said means including a pneumatic device, a valve for controlling the pneumatic device, an electro-magnetic device for controlling said valve, said electro-magnetic device comprising a solenoid connected with the valve, a switch for actuating the solenoid, a magnet for operating the switch, a shoe carried by the vehicle, contacts disposed along the track and arranged to be engaged by the shoe for completing a circuit through the switch operating magnet, said switch operating magnet being provided with a locking circuit for holding said switch when the shoe has passed the contact. 80
12. In a street indicating system for vehicles, a casing having windows, a movable flexible strip having names arranged to move past the window, means for operating the flexible strip, said means including a pneumatic device, a valve for controlling the pneumatic device, an electro-magnetic device for controlling said valve, said electro-magnetic device comprising a solenoid connected with the valve, a switch for actuating the solenoid, a magnet for operating the switch, a shoe carried by the vehicle, contacts disposed along the track and arranged to be engaged by the shoe for completing a circuit through the switch operating magnet, said switch operating magnet being provided with a locking circuit for holding said switch when the shoe has passed the contact. 85
13. In a street indicating system for vehicles, a casing having windows, a movable flexible strip having names arranged to move past the window, means for operating the flexible strip, said means including a pneumatic device, a valve for controlling the pneumatic device, an electro-magnetic device for controlling said valve, said electro-magnetic device comprising a solenoid connected with the valve, a switch for actuating the solenoid, a magnet for operating the switch, a shoe carried by the vehicle, contacts disposed along the track and arranged to be engaged by the shoe for completing a circuit through the switch operating magnet, said switch operating magnet being provided with a locking circuit for holding said switch when the shoe has passed the contact. 90
14. In a street indicating system for vehicles, a casing having windows, a movable flexible strip having names arranged to move past the window, means for operating the flexible strip, said means including a pneumatic device, a valve for controlling the pneumatic device, an electro-magnetic device for controlling said valve, said electro-magnetic device comprising a solenoid connected with the valve, a switch for actuating the solenoid, a magnet for operating the switch, a shoe carried by the vehicle, contacts disposed along the track and arranged to be engaged by the shoe for completing a circuit through the switch operating magnet, said switch operating magnet being provided with a locking circuit for holding said switch when the shoe has passed the contact. 95
